(57) **CLAIM**

We claim the ornamental design for a lighted tree ornament, as shown and described.

DESCRIPTION

FIG. 1 is a perspective view of a lighted tree ornament, showing our new design, in a used condition with a tree shown in broken lines;

FIG. 2 is a second perspective view of the lighted tree ornament;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken lines shown in the drawings represent portions of the lighted tree ornament that form no part of the claimed design.
